Primary Examiner—A. Hugo Word**Assistant Examiner**—Lavone D. Tabor**Attorney, Agent, or Firm**—Price, Heneveld, Cooper, DeWitt & Litton**[57] CLAIM**

The ornamental design for the brush, as shown and described.

DESCRIPTION

FIG. 1 is a perspective view of a brush showing my new design;

FIG. 2 is a top view thereof;

FIG. 3 is a side elevational view of one side thereof;

FIG. 4 is a bottom view thereof;

FIG. 5 is an end elevational view of one end thereof;

FIG. 6 is an end elevational view of the second end thereof; and,

FIG. 7 is a fragmentary view thereof taken from the direction of line VII—VII in FIG. 3.

The side elevational view of the second side thereof is a mirror image of FIG. 3.
